VAPORIZING-TYPE OIL BURNER HAVING
FUEL AND AIR PREHEATING MEANS

Peter Swartzentruber, Westmoreland, N. Y.

Application September 17, 1947, Serial No. 774,583

4 Claims. (Cl. 158—91)

1

This invention relates to new and useful improvements in oil burners and the primary object of the present invention is to provide a burner casing insertable in the combustion chamber of a furnace, and including novel and improved means for preheating the circulation of air controlled in said casing before mixing the same with oil fumes which are also preheated therein.

Another important object of the present invention is to provide an oil burner so designed as to produce a relatively small flame but having sufficient heat quality to efficiently produce equal or more amounts of heat than are produced by conventional oil burners now in use.

Another object of the present invention is to provide an oil burner including an air and fuel preheated mixing chamber and an outlet passage leading from said chamber, so that although large amounts of heat are developed in the chamber, there is no compression due to the outlet passage so that the same will not explode to cause harmful effects on the burner or the furnace in which the same is inserted.

Another object of the present invention is to provide an oil burner including novel and improved means for controlling the quantity of air and fuel which is conducted to the preheat mixing chamber.

Another object of the present invention is to provide a burner casing, all parts of which are quickly and readily disassembled for repair or cleaning of parts, or for convenient shipping or storing of the same.

Another object of the present invention is to provide an oil burner that is quickly and readily insertable into the fuel opening of a furnace, without in any way having to disturb the structure there present.

Another object of the present invention is to provide a safe and efficient portable oil burner, including an adjustable supporting pedestal, whereby the same may be used in conjunction with furnaces having various height fuel doors.

A further object of the present invention is to provide an oil burner using very little air in comparison with oil burners now in use, and including means for preheating the air in a fuel before mixing the same, and means for circulating the mixture of air and fuel at a high rate of speed in order to substitute speed of flow for compression, and since there is no compression in the burner casing, provide heat in place of power.

A still further aim of the present invention is to provide an oil burner that is simple and prac-

2

tical in construction, strong and reliable in use, neat and attractive in appearance, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a top plan view of an oil burner constructed in accordance with the present invention;

Figure 2 is a side elevational view of Figure 1, and with parts of the air blower broken away and shown in section;

Figure 3 is an end view of the burner casing;

Figure 4 is an enlarged longitudinal vertical sectional view of the burner casing, taken substantially on the plane of section line 4—4 of Figure 1;

Figure 5 is an enlarged longitudinal horizontal sectional view taken substantially on the plane of broken section line 5—5 of Figure 4;

Figure 6 is an enlarged transverse vertical sectional view taken substantially on the plane of broken section line 6—6 of Figure 4; and

Figure 7 is an enlarged transverse vertical sectional view taken substantially on the plane of section line 7—7 of Figure 4.

Referring now to the drawings in detail, wherein, for the purpose of illustration, there is disclosed the preferred embodiment of the present invention, the numeral 10 represents a substantially semi-cylindrical burner casing having a bottom wall 12, and a straight, substantially rectangular rear wall 14. The wall 14 has its ends projecting outwardly to form flanges 16, and its upper edge projects upwardly to form a flange 18.

Angular bearing blocks 20 are integrally formed with the bottom wall 12 and support the bottom wall 22 of a substantially semi-cylindrical mixing chamber shell 24. The upper edge of this mixing chamber shell is spaced inwardly from the upper edge of the burner casing, and the side walls and bottom wall of the mixing chamber shell are spaced relative to the side walls and bottom wall of the burner casing, to provide a preheat passage or chamber 26.

A semi-annular shoulder 28 is provided on the inner face of the mixing chamber shell 24 adjacent its upper edge, and supports the flanged portion 30 about the lower edge of a substantially

semi-cylindrical, upwardly flared lower grille 32. A notch 34 is provided in the semi-circular upper edge of the air grille 32, so that the same will frictionally engage and bear upon the upper semi-circular edge of the burner casing 10.

There is a space 36 or a continuation of the chamber 26 between the upper portion of the mixing chamber shell 24 and the lower air grille 32, and a plurality of air ports 38 provided in the air grille 32 and its flanged portion 30 communicate with the preheat chamber 26 and the mixing chamber 40 provided in the mixing chamber shell 24.

Insertable in the lower air grille 32 is the lower portion of a substantially semi-circular outwardly flared upper grille 42, having a semi-circular bottom wall 44. Air ports 46 are provided in this upper grille 42 and its bottom wall 44, and these ports 46 communicate with an air supply chamber 48 provided in the upper air grille and with the mixing chamber 40.

A semi-circular cover 50 has a semi-annular rib 52 which engages an arcuate notch 54 provided in the upper portion of the upper grille 42, and the outer edge of this cover 50 is recessed in the upper portion of the upper grille adjacent notch 54. The straight rear flanged portion or wall 56 of the cover bears upon the rear wall of the burner casing 10. Hand grips 58 are carried by the other face of the cover 50 facilitating convenient removal of the cover from the casing and the upper grille. Removably secured to the rear wall 14 and flanges 16 and 18 of the rear wall 14 are the annular flanges 60 at one of the terminals of a pair of spaced parallel tubular conduits 62.

It should be noted that a plurality of frustoconical lugs 64 are provided on the bottom wall of the shell 24 and these lugs function as heat retainers to retain the bottom wall of the shell 24 heated at all times when the instant burner is in use.

Rigidly secured to the lower periphery of the conduit 62 is a cross member 66 that is secured at its central portion to a supporting post 68 adjustably mounted in a pedestal or stand 70.

The numeral 72 represents an electrical blower motor generally, comprising an outlet box 70 and a pair of spaced parallel side conduits 76 which are removably secured to the conduits 60. Screened air intake openings 78 are provided in the sides of the conduits 76 and are regulated by pivotal closure plates 80.

The numeral 82 represents a conventional float valve housing generally, comprising a transformer 84, an oil chamber 86 and an oil level mark 88. This float valve is supported relative to the casing 10 and outwardly from the blower 72 by a bracing and supporting member 90, one terminal of which is rigidly secured to the valve housing 82 and the opposite terminal of which is connected to cross member 66.

In practical use of the device, a fuel line 92 leads from the oil chamber 86 to the mixing chamber 40, and the burner head is inserted into the fire pit of a furnace (not shown). The flow of the fuel in the line 92 is controlled by conventional needle valves (not shown) in the float casing. It should be noted that, as indicated at numeral 94, a plurality of lines lead from the float valve. Two of these lines are connected to the main line; a second pair of wires lead from the float valve to a thermostat (not shown); two further wires lead from the safety valve to the motor switch (not shown); and a still further pair of wires lead

from the safety valve to a pressure gauge which is conveniently mounted on the furnace (not shown).

The operation of the device is as follows: Air 5 enters chambers 48 and 26 from the blower and the air is forced to circulate through these chambers and contacts the cast iron material of which the upper grille, lower grille, and mixing shell are constructed; these elements, namely, the upper grille, lower grille and mixing chamber shell are intentionally hot at all times and as the circulated air contacts the same, the air will be preheated, and since the burner is of a continuous flow type, these casings never cool down; the preheated air is forced through the ports in both the upper and lower air grilles and enters the mixing chamber 40; oil enters by gravity into the mixing chamber, and as it enters it spreads out very thinly over the bottom wall of the mixing chamber shell, and as the shell is very hot, the lugs on the bottom wall of the shell near the heat of the burner partake of the heat and aid in retaining the bottom wall of the shell intensely heated at all times; the oil will turn to a vapor and fumes 15 due to the heat in the mixing chamber, the heated air and oil fumes mix and escape through an outlet passage 96 between the upper and lower grilles to produce the desired heat. These preheated fumes of oil, gases and oxygen travel at 20 a rapid speed and will burst into a flame at the entrance of the outlet passage with the mixing chamber, and since there is no compression in the burner, the energy produced will be heat rather than power, so that a maximum efficiency 25 can be obtained by controlling the mixture of air and fuel within the mixing chamber.

Having described the invention, what is claimed as new is:

- 40 1. An oil burner comprising a burner casing including a bottom wall, a straight rear wall and an arcuate wall joining the rear wall of said casing at its ends, upstanding support lugs integrally formed with the bottom wall of said casing, a mixing chamber shell supported on said lugs, the walls of said shell being spaced laterally from the walls of said casing to provide an air passage, an arcuate shoulder provided on the inner surface of said shell, an arcuate outwardly and upwardly flared first air grille having upper and lower end portions, a flange at the lower end portion of said first air grille supported on shoulder, a notch provided in the upper end portion of said first air grille receiving the upper edge of the arcuate wall for said casing, said first air grille and said flange being provided with apertures, a second arcuate, upwardly and outwardly flared air grille having an apertured, semi-circular bottom wall spaced above the bottom wall of said shell, said semi-circular bottom wall including a diametrical edge abutting the straight wall of said casing, the upper end of said second grille being supported upon the straight wall of said casing and extending above the casing, said second grille being spaced inwardly horizontally, from said first grille to provide an outlet passage therebetween, a cover supported on the upper end of said second air grille and including a depending relatively straight flanged portion supported on the rear wall of said casing, said second air grille having a plurality of apertures therein, a fuel supply conduit extending through the rear wall of said casing and the rear wall of said shell for supplying fuel to said shell, said rear wall of said casing having openings adjacent each end thereof, a pair of air supplying conduits carried by the
- 45
- 50
- 55
- 60
- 65
- 70
- 75

rear wall of said casing and communicating with the openings in said rear wall, means for directing air through said conduits, and means for introducing a regulated supply of fuel through said fuel supply conduit.

2. An oil burner comprising a burner casing having a bottom wall, a straight rear wall and an arcuate wall joining the rear wall of said casing at its ends, a shell positioned loosely within said casing and spaced from the walls of said casing to provide a preheating space between the walls of said casing and the walls of said shell, means rising from the bottom wall of said casing supporting the shell, a shoulder on the inner surface of said shell, an arcuate outwardly and upwardly flared first air grille having an upper portion and a perforated lower portion, the lower portion of said first air grille being received in said shell and supported upon said shoulder, the arcuate wall of said casing having an upper edge supporting the upper portion of said first air grille, said flared portion of said first air grille having a plurality of openings therein, a second arcuate, upwardly and outwardly flared perforated air grille having an apertured semi-circular bottom wall spaced above the bottom wall of said shell, said semi-circular bottom wall including an edge abutting the straight wall of said casing, said second air grille having an upper portion extending above the casing, said second air grille being spaced inwardly, horizontally, from said first grille to provide an outlet passage therebetween, a cover supported on the upper end of said second air grille and including a depending flanged portion supported on the rear wall of said casing, said cover being spaced above the rear wall of said casing, means for supplying fuel to said shell, and means for admitting a supply of air through the preheating space to the shell.

3. A liquid fuel burner comprising a burner casing having a bottom wall, a rear relatively straight wall and an arcuate wall joining the rear wall of said casing at its ends, a mixing chamber shell having a bottom wall, a relatively straight rear wall and an arcuate wall joining the rear wall of said shell at its ends, said shell being received within said casing and having its walls spaced inwardly of the walls of said casing to define a preheating space between said casing and said shell, blocks rising from the bottom

wall of said casing supporting said shell above the bottom wall of said casing, a first arcuate air grille having ends resting against the rear wall of said shell, said first air grille being concavo-convex and including an upper portion and a perforated lower portion, a shoulder on the convexed surface of said shell supporting the lower portion of said first air grille, the upper portion of said first air grille extending over and being spaced from the arcuate wall of said shell, the upper portion of said first air grille being supported on the arcuate wall of said casing, a second arcuate perforated air grille having a concavo-convex wall and a bottom wall, the bottom wall of said second air grille bearing against the rear wall of said shell, said second air grille having upper and lower portions, the lower portion of said second air grille being received within the lower portion of said first air grille, the concaved surface of said second air grille being spaced from the convexed surface of said first air grille to provide an outlet, a cover supported by said second air grille and having a depending flanged portion resting upon the rear wall of said casing, said cover being spaced above the rear wall of said casing, means for supplying fuel to said shell, and means for supplying air through the preheating space to the shell.

4. The combination of claim 3 and heat conducting lugs integrally formed with and rising from the bottom wall of said shell, said lugs being spaced from the bottom wall of said second air grille and also spaced from the lower portion of said first air grille.

PETER SWARTZENTRUBER.
